UNITED STATES PATENT OFFICE.

HOWARD D. COLMAN, OF ROCKFORD, ILLINOIS, ASSIGNOR TO HOWARD D. COLMAN, LUTHER L. MILLER, AND HARRY A. SEVERSON, COFARTNERS TRADING AS BARBER-COLMAN COMPANY, OF ROCKFORD, ILLINOIS.

TEXTILE APPARATUS.

1,245,874.

Specification of Letters Patent.

Patented Nov. 6, 1917.

Application filed April 7, 1913. Serial No. 759,278.

To all whom it may concern:

Be it known that I, HOWARD D. COLMAN, a citizen of the United States, residing at Rockford, in the county of Winnebago and State of Illinois, have invented certain new and useful Improvements in Textile Apparatus, of which the following is a specification.

This invention relates to winders or spoolers, and particularly to the operations of replacing empty bobbins with full bobbins, and full spools or cheeses with empty spools or cheese-cores. Heretofore it has been customary to place supplies of full bobbins and empty spools or cheese-cores at points adjacent to the spooler or winder, the operatives going to these sources of supply whenever necessary; and the full spools or cheeses have been carried away from the spooler or winder and deposited in suitable receptacles for transportation to the warper creels. This manner of supplying material to the winder and disposing of the product has necessitated a great many movements on the part of the operatives, with consequent expenditure of time and strength, and the frequent handling and re-handling of bobbins and cheeses.

The object of this invention, generally stated, is to reduce to a minimum the amount of labor necessary in the performance of the operations of replacing bobbins and cheeses on winders and spoolers, by providing means whereby the operative has constantly at hand a supply of the articles needed in the performance of her duties, and whereby the operative may move to various points along the winder with as little exertion and loss of time as possible.

The invention also contemplates a reduction in the number of handlings to which the spools or cheeses are subjected, by providing the winder operative with receptacles or supports for the full spools or cheeses, which receptacles or supports are of such character that they may be transported to and used in the creels of the warpers with the least possible handling of the spools or cheeses.

In the accompanying drawings, Figure 1 is an inner side view of a truck comprised in an embodiment of my invention. Fig. 2 is a top plan view of said truck, together with a portion of a winder or spooler in con-

junction with which the truck is used. Fig. 3 is a right-hand end elevation of the truck and a fragmental end elevation of the winder. Fig. 4 is a sectional view of a vertically adjustable platform or table intended to support bobbin boxes. Fig. 5 is a fragmental view of the winder. Fig. 6 is a view of the left-hand end of the truck. Figs. 7 and 8 are fragmental views, illustrating the construction and operation of the propelling means for the truck. Fig. 9 is a fragmental sectional view of the means for raising and lowering the bobbin box platform. Figs. 10 and 11 are views of a portion of the means for supporting the operative's seat.

The truck hereinbefore referred to is arranged for movement upon rails 1 placed alongside the spooler or winder, and is arranged to support the operative, a supply of full bobbins, a supply of cheese-cores, a receptacle for full cheeses, and a receptacle for bobbins which, on account of some defect, cannot be unwound on said winder. The truck is provided with pedal-actuated propelling means, in order that the operative may, with little exertion, move herself and the articles she needs in performing her duties, to any point along one side of the winder. A similar truck is provided at the opposite side of the winder.

The truck may be used in connection with spoolers or winders of the ordinary or any preferred type. Herein I have indicated portions of an automatic winder. The numeral 2 in Fig. 3 designates portions of the framework of the winder, and 3 and 4 denote a pair of bobbin-holders. One of these bobbin-holders supports the bobbin which is being unwound to form a cheese, while the other bobbin-holder contains a reserve bobbin. A pair of bobbin-holders and the corresponding cheese-supporting and rotating means may be termed a winder-unit, each side of the winder consisting of a considerable number of such units.

The winder comprises an automatic mechanism (not herein shown) which is arranged to travel in an endless circuit, so as to operate in succession upon the units forming the two sides of the winder, said mechanism acting to tie the end of the thread on the reserve bobbin to the end of the thread on the cheese. The speed of winding and the time consumed by the uniting mecha-

nism in making one complete circuit of the winder are so proportioned to one another that the unwinding of each bobbin will be completed just prior to the arrival of the 5 uniting mechanism into operative relation to the respective bobbins. In practice, the operative, seated upon the truck herein shown, follows the uniting mechanism, replacing the exhausted bobbins with reserve 10 bobbins, and replacing the cheeses, when full, with empty cheese-cores. It may be here stated that the cheeses are never wholly unwound in the warper. When empty cheese cores are herein mentioned, it will be understood 15 that the cores are only relatively empty.

In the winder framework is arranged, at a suitable height, a shelf or platform 5 (Fig. 3) to receive boxes containing full bobbins. 20 Preferably these boxes are those employed with portable spinning-frame doffers, such a box, for example, as is shown in patent No. 983,858. Herein the boxes are indicated at 6. They may be transported directly 25 from the spinning room to the shelf 5 and arranged thereon in two rows extending longitudinally of the winder, as represented in the drawings. Boxes 7 to receive empty bobbins are placed upon the floor beneath 30 the shelf 5.

The truck may be of any suitable construction. Herein I have shown it as comprising a rigid frame 8 supported on the axles 9 and 10, said axles having wheels 11 mounted thereon. The wheels are adapted 35 to roll upon the rails 1.

12 is a seat for the operative, said seat being fixed to an arm 13 having a sleeve portion 14 (Fig. 11) which is rotatably 40 mounted upon a pivot 15 fixed to a standard 16 rising from the frame 8. The sleeve 14 is supported at the desired height by means of a collar 17 which is vertically adjustable on the pivot 15 but is held against rotation 45 by a key 18. A set screw 19 provides means for securing the collar 17 in adjusted position. In order to releasably hold the seat 12 in operative position, the sleeve 14 is provided with a beveled rib 20 and the collar 17 50 with a similarly formed groove 21 to receive the rib when the seat is in operative position.

Fixed to the arm 13 is a horizontal arm 22 which normally extends inwardly and 55 has fixed to its inner end a pad 23.

The seat 12 is supported to swing upon the axis of the pivot 15 in order to enable the operative to enter and leave the truck conveniently. Assuming the seat 12 and the 60 pad 23 to occupy the positions shown in dotted lines in Fig. 2, the operative steps upon the truck and swings the seat into operative position by pressing against the pad.

The means for propelling the truck may 65 be of any suitable character. Herein I have

shown two pedals 24 and 25 located in operative relation to the seat, and fixed upon rock shafts 26 and 27, respectively. These rock shafts are mounted in bearings on the frame 8 and extend longitudinally thereof. 70 On the shaft 26 is fixed a bevel gear segment 28 (Figs. 6 and 7) that meshes with a similar segment 29 rotatably mounted upon the axle 10. To the segment 29 is fixed a crank arm 30 to which is pivoted a 75 pawl 31 arranged to engage a ratchet wheel 32 fixed on the axle 10. A spring 33 tends to move the pawl into engagement with the ratchet wheel. A spring 34 anchored at one end to the frame 8 and attached at its other 80 end to a crank arm 35 fixed on the rock shaft 26 tends to hold the pedal 24 in normal position. 36 is a pin fixed in the pawl 31. When the spring 34 restores the pedal 24, shaft 26 and crank arm 30 to normal 85 position, the pin 36 rides up on a stationary cam plate 37, whereby the pawl 31 is withdrawn from the ratchet wheel 32. A stop 38 limits the action of the spring 34. 39 is a stop to limit the active stroke of the 90 pedal 24.

The parts communicating motion from the pedal 25 to the axle 10 are substantially similar to those just described, and are indicated in the drawings by the same numerals with exponents added. The two ratchet mechanisms operate in opposite directions. A shaft 40 hereinafter described serves as a stop to limit the active movement of the pedal 25. Both pedals have 95 approximately the same range of movement.

In following the uniting mechanism, the operative moves the truck to the right by operating the pedal 24, the extent of movement imparted to the truck by one depression of the pedal 24 being approximately the same as the distance between two adjacent winder-units. In returning to the starting point, the operative uses the pedal 25, the gearing 28^a and 29^a being such that 10 the return movement may be accomplished with fewer strokes of the pedal than are necessary in the working trip.

At the point upon the truck which is convenient to the right-hand of the operative is 11 a chute 41 for conducting empty bobbins to the boxes 7. 42 is a guard plate fixed in proper relation to the receiving end of the chute 41 to stop bobbins tossed against said plate by the operative, and insure that 12 such bobbins shall pass into the chute. To prevent bobbins from sliding out of the chute into the spaces between the boxes 7, I place upon the frame members 2 between 13 said boxes stop members 43 (Fig. 5) which extend across the space between two adjacent boxes and close the end of the chute while the latter is traveling from one box to the next. The ends of the stop members 43 are made wedging so as to cam up 14

and release any bobbin that might become caught between a side wall of the chute and the end of the stop member.

Means for supporting a supply of full bobbins is provided at the left-hand side of the seat 12. Said means comprises, in this instance, a revolute platform 44. This platform is adapted to support two bobbin boxes 6, the platform being made rotatable so that the operative may conveniently bring either box into position adjacent to the seat. The platform is also made vertically adjustable in order that the boxes may be raised as the level of their contents is lowered and thus obviate the necessity of stooping to pick up bobbins.

In the construction herein shown, the platform 44 is fixed to a plunger 45 (Fig. 4) which is rotatable and slidable in a cylinder 46 secured in a vertical position upon the frame 8. When in its lowermost position, the top of the platform 44 is in the horizontal plane of the top of the shelf 5, so that the operative may readily push an empty box 6 off said platform onto the shelf 5 and pull a full box off the shelf onto the platform.

The platform 44 may be raised by means of a pump 47 (Fig. 9) arranged to force a suitable liquid into the cylinder 46. Said pump comprises a cylinder 48 having an inlet and outlet port 49, and a piston 50, the rod 51 of which is connected to a pedal 52. The suction movements of the piston 50 are imparted to it by a spring 53. Communicating with the port 49 is a check-valve-controlled inlet 54 located within a reservoir 55. A line of pipe 56 extends between the port 49 and the lower end of the cylinder 46, said line of pipe including a check valve 57. When the piston 50 is forced downwardly, the oil or other liquid is forced from the cylinder 47 into the pipe 55, past the check valve 57 and to the cylinder 46, thereby raising the plunger 45 some distance in the cylinder 46. The platform 44 may thus be gradually raised by the operative in order to keep a supply of bobbins close at hand. At a point in the cylinder 46 determining the upper limit of movement of the platform is an outlet port 58 communicating with a return-flow pipe 59, said pipe leading to the reservoir 55. Included in the line of pipe 59 is a pressure-relief chamber 60 to allow the liquid to escape quickly through the port 58 when said port is opened by the rising of the plunger 45. 60^a is an air vent hole in the top of the reservoir 60.

To permit of lowering the platform 44 I provide a discharge valve 61 in the pipe 56 within the reservoir 55, said valve being operable by means of a pedal 62 fixed to the shaft 40, said shaft being connected through 35 a crank arm 63 and link 64 to one arm of a

bell crank lever 65, the other arm of said lever bearing against the stem of the valve 61. A spring 66 normally holds the valve 61 closed and holds the pedal 62 in initial position.

Oil leaking up along the plunger 45 is conducted to the return-flow pipe 59 by an annular groove 67 in the upper end of the cylinder, a duct 68 and a pipe 69. Any oil that may leak up past the piston 50 is returned to the reservoir 55 through the annular space 70 and duct 71.

At the right-hand side of the seat 12 is means to support the cheeses removed from the winder. Said supporting means consists of a revolute platform or table 72 supported at a convenient height upon the truck.

The platform 72 is adapted to support a plurality of warper-creel elements. The form of creel element herein shown may be termed a "trident" and consists of a base *a* to which are attached three spindles, each spindle having four bushings or sleeves *b* rotatably mounted thereon. The cheese-cores are adapted to be slipped over said sleeves. The tridents are removed from the warper creels, with the empty cheese-cores remaining in position thereon, and placed upon a table 73 located at the right-hand end of the path of movement of the truck. The top of the table 73 is in the horizontal plane of the top of the platform 72. The side of the table 73 facing the truck is recessed as at 73^a (Fig. 1), to conform to approximately one-half of the periphery of the platform 72, so that when said platform is placed against the table the operative can push filled tridents onto the table and pull empty tridents off the table and onto the platform.

A box 74 is removably supported on the truck beneath the platform 72, said box being intended to receive bobbins which cannot be unwound on the winder. The box stands upon two bars 75, and may be inserted and removed from the front (or outer) side of the truck.

In practice, the operative follows the uniting mechanism, removing the spent bobbin from the bobbin-holder of each winder-unit, tossing said bobbins into the chute 41, taking full bobbins from a box 6 on the platform 44, placing said full bobbins in the bobbin-holders previously occupied by spent bobbins, and placing the ends of the yarn on said full bobbins in position for action thereon by the uniting mechanism on its next visit. The operative also removes from the winder any cheeses that may be full or complete, placing such cheeses onto a spindle of a trident, taking empty cheese-cores off another trident-spindle, and placing such empty cheese-cores upon the winder-units from which the full cheeses were removed.

It will be seen that this invention provides means for greatly economizing the time of

70

winder operatives, thus rendering it possible for an operative to care for a greater number of units than would otherwise be possible.

5. By minimizing the amount of handling to which the cheeses are subjected, the invention not only saves labor, but also obviates the danger of damage to the cheeses resulting from the previous methods of handling 10 and piling.

I claim as my invention:

1. A winder truck comprising a wheeled frame, a seat thereon for the operator, a support on said frame for supporting yarn 15 masses within convenient reach of the operator's hands while the operator is seated upon said seat, means for adjusting the position of said support with relation to the wheeled frame, and a pedal for actuating said adjusting means, said pedal being within convenient reach of the operator while the operator is seated upon said seat.
2. A winder truck comprising a wheeled frame, a seat thereon for the operator, a rotatable support for yarn masses, said support being located at one side of the seat, means on said frame for raising and lowering said support to bring the yarn masses 20 within convenient reach of the hands of the operator while the operator is seated on said seat, and a pedal on said frame for actuating said raising and lowering means, said pedal being located within convenient reach of the feet of the operator while the operator 25 is seated on said seat.
3. A winder truck comprising a wheeled frame, a pawl and ratchet mechanism for driving the truck in one direction only, a

pedal for actuating said pawl and ratchet mechanism, a pawl and ratchet mechanism 40 for propelling the truck in the opposite direction only, a pedal for actuating the last-mentioned pawl and ratchet mechanism, and a seat located on the truck in operative relation to said pedals.

4. A winder truck comprising a wheeled frame, a seat supported on said frame for pivotal movement in a horizontal plane, and a member extending forwardly of the seat and at one side thereof in position for engagement by the knee of the operator, said member being arranged to swing with the seat.

5. A winder truck comprising an elongated wheeled frame, a seat located centrally of the frame and facing one side thereof, a mechanism for propelling the frame in one direction only, a mechanism for propelling the frame in the opposite direction only, two 50 pedals each for actuating one of said mechanisms, said pedals being located in front of the seat, two load supports located at opposite sides of the seat in position to support the loads within convenient reach of the hands of the operator when the operator is seated on said seat, and means for raising and lowering one of said load supports, said raising and lowering means including a 55 pedal located in front of the seat.

In witness whereof, I hereby affix my 60 signature in the presence of two witnesses.

HOWARD D. COLMAN.
